CLAIM

The ornamental design for hair spray deflector, as shown and described.

DESCRIPTION

FIG. 1 is an isometric front view of the hair spray deflector showing my new design;

FIG. 2 is a top view thereof;

FIG. 3 is a front view thereof;

FIG. 4 is a side elevational view, the side opposite being a mirror image of the side shown;

FIG. 5 is a bottom view thereof; and,

FIG. 6 is a back view thereof.
